UNITED STATES PATENT OFFICE.

WALTER A. THOMAS, OF NEW AUGUSTA, INDIANA.

CULTIVATOR-FENDER.

1,079,197.

Specification of Letters Patent.

Patented Nov. 18, 1913.

Application filed November 29, 1912. Serial No. 734,171.

To all whom it may concern:

Be it known that I, WALTER A. THOMAS, a citizen of the United States, residing at New Augusta, in the county of Marion and State 5 of Indiana, have invented certain new and useful Improvements in Cultivator-Fenders; and I do hereby declare the following to be a full, clear, and exact description of the invention, such as will enable others skilled in 10 the art to which it appertains to make and use the same.

My invention relates to an improved fender for the plows of a cultivator.

The object of my improvement is to provide a fender of such construction as to render it readily attachable to the ordinary forms of riding cultivators, and means thereon for conveniently raising the fender out of operative position by the foot of the 20 operator.

A further object is to provide a guard for clearing the path of the fender of stalks or other obstructions.

In the drawings, Figure 1 is a perspective 25 view of my improved fender as applied to use upon a plow beam of ordinary construction, and, Fig. 2 is a sectional view on the line 2—2 of Fig. 1.

Referring to the drawings, wherein like 30 reference numerals designate corresponding parts throughout the several views, 1 represents the main plow beam of a riding cultivator having the auxiliary beams 2 and 3 connected therewith at different points longitudinally of the main beam. Each of the beams is provided with the ordinary form of plow point 4.

Pivoted to the forward portion of the main beam 1 is the supporting arm 5 40 of the fender blade 6. The rear end of the blade 6 is provided with an upwardly extending and vertically adjustable arm 7, having the upper end offset and pivoted to the rear end of the lever 8 of the pedal 9, the forward end of the lever 8 being bent or crooked to provide an upwardly inclined 45 pedal 9.

The forward end of the lever 8 is pivoted within the looped portion of bracket 10 se-

cured to the auxiliary beam 3 and braced 50 against the main beam 1 by the bolt 11, one of the ends of said bracket being bent into engagement with the under side of the auxiliary beam 3 for more securely supporting it in position. By means of the pivot at 55 the forward end of the arm 5, the blade 6 is allowed to move downwardly by gravity until the curved pedal end 9 of the lever 8 engages against the front face of the looped portion of the bracket 10, and to adjust the 60 blade 6 vertically, relative to the points 4, it is merely necessary to remove the bolt 12 securing the arm 7 to the blade 6 and engaging it with any desired of the spaced openings in the lower end of said arm. 65

The forward portion of the arm 5 is offset or bent outwardly from the main beam 1 in order to avoid the plow points of the cultivator, and to said offset portion is secured an angle iron 13, having secured thereon, directly forwardly of the blade 6, the vertically adjustable stalk guard 14, having the brace arm 15 connected thereto and adjustable to the angle iron 13. The stalk guard 14 and brace arm 15 are each provided with 70 75 slots through which are secured bolts 16.

What I claim is:—

The combination with the main and auxiliary beams of a cultivator, of an arm pivoted to the main beam and carried thereby, a 80 bracket having a looped portion and downwardly directed ends secured to an auxiliary beam, a lever pivoted in the looped portion of said bracket, the front end of said lever being turned upwardly and normally resting 85 against the front face of said bracket for supporting the rear end in a horizontal plane, and a link pivoted at one end to the rear end of the lever and adjustably secured at the opposite end to the blade. 90

In testimony whereof I have signed my name to this specification in the presence of two subscribing witnesses.

WALTER A. THOMAS.
